FIG. 1.

FIG. 2.

FIG. 3.

FIG. 4.

My Bright & Dailey
Attorneys

Patented Dec. 28, 1926.

UNITED STATES PATENT OFFICE.

GEORGE ELDEN HALL, OF CONCORD, NEW HAMPSHIRE.

HORSESHOE.

Application filed September 15, 1924. Serial No. 737,761.

My invention relates to shoes for use particularly on racing horses and on light horses for road work, my purpose being to provide a shoe that is light and durable, that gives an even bearing over the entire under surface of a hoof, that will prevent the entrance of gravel and dirt between the shoe and the hoof, that will retain a slight amount of moisture sufficient to keep the hoof in good condition, and, above all, that will cushion the blows of a horse's hoofs striking the ground, so as to relieve the legs and shoulders of shocks and jars.

With the foregoing and other purposes in view, my invention consists in the novel features of construction, combination and arrangement of parts as will be hereinafter more fully described, illustrated in the accompanying drawings and defined in the appended claims.

In the drawings, wherein like characters of reference denote corresponding parts in the different views—

Figure 1 is a bottom plan view of a horseshoe embodying the novel and essential features of my invention;

Fig. 2, a top plan view;

Fig. 3, a central longitudinal section through the shoe; and

Fig. 4, a central transverse section.

As illustrated in the drawings my improved horseshoe consists essentially of a sole 10, a sack 11 secured to the upper side of said sole, and a pad 12 of cushioning material within said sack.

The sole 10 which may be formed from leather, rubber or other suitable material, is cut to the shape of the under face of a hoof and is provided at suitably spaced intervals near its periphery with nail openings 13.

Sack 12 likewise may be formed from any suitable material, such as chamois, and is produced in relatively flat form and of substantially the same size and shape as sole 10.

Within sack 12 is arranged a thin metallic plate 14 also of substantially the same size and shape as sole 10, and through this plate and the sole are engaged rivets 15 which serve to clamp one side of the bag between the sole and said plate and thereby secure the sack to the upper face of the sole as is obvious. One or more of the rivets 15 also are passed through a wear plate 16 engaged against the under face of the sole at

the toe portion thereof to secure such wear plate to the sole.

The top side of sack 11 is slotted as at 17 to permit insertion of the pad 12 of cushioning material, such as felt, within the sack, and to permit removal of a compressed or otherwise undesirable pad and the insertion of another in lieu thereof.

Although unnecessary, the under face of the sole 10 preferably is recessed as at 18 for the reception of wear plate 16, so that if only a single securing rivet is engaged through said plate, it still will be prevented from turning out of correct relation with respect to the sole.

To apply the shoe to a hoof, nails are driven through the openings 13 and through the pad 12 and sack 11 into the hoof in the usual well known manner, and when the shoe thus is attached in place with the pad 11 between the hoof and the sole 10, the legs and shoulders of the animal so shod will be relieved of shocks and jars by the cushioning action of the pad, as is apparent. Furthermore, the soft, pliable nature of the sack with the pad therein will result in the sack fitting closely any irregularities in the hoof, so that there will be an even pressure of the shoe against the hoof and gravel and dirt will be excluded from between the shoe and the hoof.

I claim:

1. A horseshoe comprising a sole adapted to cover the entire bottom of a hoof, a sack attached to the upper side of said sole, and a pad of cushioning material retained within the sack, said sack and pad, when the shoe is applied to a hoof, covering the entire upper side of the sole and the entire bottom of the hoof.

2. A horseshoe comprising a sole, a slotted sack attached to the upper side of said sole, and a pad of cushioning material retained within said sack, said pad being insertable within and removable from said sack through the slit therein.

3. A horseshoe comprising a sole, a sack, a plate within said sack, means fastening said plate to said sole to maintain the sack attached to the sole, and a pad of cushioning material within said sack.

4. A horseshoe comprising a sole, a sack, a plate within said sack, rivets extending through said plate and sole to clamp a portion of the sack between the sole and plate

thereby to secure the sack to the sole, and a pad of cushioning material within said sack.

5. A horseshoe comprising a sole, a sack on the upper face of said sole, a plate within said sack, a wear plate on the under face of said sole, a fastener extending through said wear plate, said sole, and the plate

within said sack, thereby to secure said wear plate and said sack to the sole, and a pad of cushioning material within said sack.

10 In testimony whereof I hereunto affix my signature.

GEORGE ELDEN HALL.
